LOUD-SPEAKER

Mildred F. Lucas, St. Charles, Ill., assignor to
Operadio Manufacturing Co., St. Charles, Ill.,
a corporation of Illinois

Application November 15, 1943, Serial No. 510,325

2 Claims. (Cl. 179—115.5)

This invention relates to loudspeaker units designed for use with radio receivers, public address systems and the like, and it is particularly directed to supporting means for the conducting cables which are included in such units.

One object of the invention is to provide a new and improved loudspeaker unit for radio receivers and the like.

Another object of the invention is to provide an improved support for a conductor cable closely associated with a loudspeaker unit.

More specifically, it is an object of the invention to simplify the construction and to eliminate a possible source of vibration in a loudspeaker unit by forming the frame member which encompasses the transformer of the unit with an integral lug of sufficiently pliable material to be bent around a cable of lead wires of the transformer and other parts of the speaker to provide support for such cable in proper relation to the unit.

Other objects and advantages of the invention will appear from the following description taken in connection with the drawing in which:

Fig. 1 is a rear elevational view of an electrodynamic type of speaker unit embodying this invention.

Fig. 2 is a side elevation of the same.

Fig. 3 is a rear elevation with a portion broken away, showing a permanent magnet type of speaker unit with this invention applied thereto.

Fig. 4 is a side elevation of the same.

Fig. 5 is a perspective view of a transformer frame member having a special lug for supporting a cable in accordance with this invention.

While the invention is susceptible of various modifications and alternative constructions, the embodiments shown in the drawing and described hereinafter are by way of preferred illustration only, and it is not intended that the invention be limited thereto or thereby, but it is the intention to cover all modifications and alternative constructions falling within the scope of the invention as defined by the claims.

Figs. 1 and 2 show a typical loudspeaker unit of the electrodynamic type including a main frame 1, usually stamped from sheet metal and supporting a speaker cone 10, together with a field coil indicated at 2 and a transformer indicated generally at 3. Lead-in wires 4 for the transformer and lead wires 5 for the field coil are combined in a cable 6 provided with a terminal plug 7 for connecting the speaker into the circuit of a radio receiver, public address system or other like apparatus. The transformer 3 includes cover shells

8, 8 for its coil and a rectangular frame 9 which may be formed of sheet metal with side flanges 9^a giving the frame a channel shape so that it encompasses the transformer coil on three sides, 5 encloses the plates of the transformer at their edges and retains in position the cover shells 8, 8 by overlapping engagement with marginal flanges thereof. The frame 9 is provided with perforated lugs 11 and 12 through which fastening bolts 13 10 extend into securing engagement with portions of the frame 1.

In accordance with this invention the lug 12 is made considerably longer than the lug 11, and its terminal portion 12^a is sufficiently pliable so that 15 it can be readily bent around the cable 6 to encompass the latter and hold it in proper relation to the parts of the speaker to prevent any strain on the lead wires 4 and 5 which might tend to break or disturb the electrical connections. This 20 extension of the lug 12 to serve as a support for the cable avoids the use of a separate supporting member and precludes the possibility of such separate support becoming loosened or being slightly spaced from an adjacent part so that it 25 would vibrate during operation of the speaker or in response to tones of certain pitch, thus impairing the clarity of tone of the instrument. Such vibration might even become severe enough to completely loosen a separate supporting lug, permitting it to swing out of its originally clamped position, whereas the integral lug 12^a, extending from the foot or mounting lug 12 of the frame 9, is permanently located when it is once bent around the cable 6.

35 Figs. 3 and 4 illustrate a speaker unit of the permanent magnet type in which the frame 21 supports a cone 20 and a voice coil 22, together with a transformer unit 23. The lead wires 24 for the transformer are carried in a cable 25 to a terminal plug 26 and the transformer cover shells 8, 8 are held in place by the rectangular frame 9 with its side flanges 9^a, this frame being similar in all respects to the frame 9 shown in Figs. 1 and 2. The frame is secured to a mounting bracket 28 by foot flanges 11 and 12, and the flange 12 is extended at 12^a and curled around the cable 25 to provide support therefor in the same manner as the lug 12^a of Fig. 1.

40 Fig. 5 illustrates the frame 9 as it appears when removed from the transformer, with its side flanges 9^a forming an inwardly open channel structure to engage the plates and cover shells of the transformer, and with its foot flanges 11 and 12 perforated to receive securing bolts, as 45 described. The portion 12^a is shown extending

from the flange 12 and curled in its final position, a fragment of cable being indicated in dotted outline at 8 as extending through the curled lug 12a. In accordance with standard construction, the cable 8 is made with a relatively soft outer jacket of insulating material; and while the extending portion 12a of the lug 12, projecting beyond the bolt 13 by which the lug is clamped to the speaker frame or to a bracket thereon, would have a tendency to vibrate, at least sympathetically, in response to certain tones of the speaker, its close contact with the soft covering of the cable 8 will cause said covering to damp any vibrations of the lug 12a.

I claim as my invention:

1. In a loudspeaker unit, a transformer with a frame member encompassing said transformer and having perforated lugs with fastening members extending through said lugs and into a part of said unit for securing of the transformer on the unit, and a conductor cable extending

from an attachment plug and including lead wires for the transformer, one of said lugs having an integral extension bent around and gripping said cable to support it in proper relation to the transformer.

2. In a loudspeaker unit, a main frame, a diaphragm supported thereon, a field coil secured to the frame, a transformer including a metallic frame fitted over the transformer and having integral perforated lugs, clamping members extending through the perforations of said lugs and securing said lugs rigidly to said main frame, and a cable including all the inleading wires for the speaker, said cable terminating in a detachable connecting plug and having a relatively soft insulating jacket, one of said lugs of the transformer frame having an integral extension bent around said cable embracing and gripping said soft jacket to support said cable, said jacket serving to damp vibration of said lug.

MILDRED F. LUCAS.
